SYRINGE

Harold Hershenson, Burbank, Calif., assignor to Pharma-seal Laboratories, Glendale, Calif., a corporation of California

Filed Jan. 29, 1962, Ser. No. 68,557

Term of patent 14 years

(Cl. D83—1)

FIG. 1.

FIG. 2.

FIG. 3.

FIG. 4.

FIG. 5.

FIGURE 1 is a front elevational view of a syringe showing my new design;

FIGURE 2 is a top plan view thereof;

FIGURE 3 is a sectional view on line 3—3 of FIGURE 1;

FIGURE 4 is a bottom plan view thereof; and

FIGURE 5 is an enlarged fragmentary perspective view of the discharge spout member.

The rear and sides of the syringe are substantially identical to the front of the syringe shown in FIGURE 1.

I claim:

The ornamental design for a syringe, as shown and described.
